CLAIM

The ornamental design for a cocktail smoker, as shown and described.

DESCRIPTION

FIG. 1 is a top perspective view of a cocktail smoker, showing my new design.

FIG. 2 is a bottom perspective view thereof.

FIG. 3 is a front elevational view thereof.

FIG. 4 is a rear elevational view thereof.

FIG. 5 is a left side elevational view thereof.

FIG. 6 is a right side elevational view thereof.

FIG. 7 is a top plan view thereof; and,

FIG. 8 is a bottom plan view thereof.

The broken line showing of cocktail smoker for the purpose of illustrating portions of the cocktail smoker and forms no part of the claimed design.

1 Claim, 8 Drawing Sheets(56)
